UNITED STATES PATENT OFFICE.

LUDWIK RZEPKA, OF CHICAGO, ILLINOIS.

LOCK.

Application filed November 2, 1921. Serial No. 512,282.

To all whom it may concern:

Be it known that I, LUDWIK RZEPKA, a citizen of Poland, residing at Chicago, in the county of Cook and State of Illinois, 5 have invented certain new and useful Improvements in Locks, of which the following is a specification.

This invention relates to certain new and useful improvements in locks and has particular reference to a lock especially designed for doors wherein a pair of independently operable latch bolts are provided for retaining the door in locked condition.

A further object of the invention has reference to a door lock wherein a pair of tensioned latch bolts is contained within the lock casing with means associated with the latch bolts for moving the same to a position to permit opening movement of the 20 door.

A still further object of the invention embodies in a door lock, a pair of tensioned latch bolts, one of the latch bolts being moved to a retracted or inoperative position 25 and so retained under control of a key while the other latch bolt may be employed in the usual manner and operable by the spindle of the door knob.

With the above general objects in view 30 and others that will appear as the nature of the invention is better understood, the same consists of the novel form, combination and arrangement of parts hereinafter more fully described, shown in the accompanying drawings and claimed.

In the drawings, wherein like reference characters designate corresponding parts throughout the several views,

Figure 1 is a front elevational view of 40 a lock and casing constructed in accordance with the present invention,

Figure 2 is a fragmentary vertical section, partially broken away of a door frame with the lock mounted therein,

Figure 3 is a fragmentary sectional view 45 of a portion of a door and frame showing the mechanism of the lock with the cover of the lock casing removed, the lock being illustrated in locked condition,

Figure 4 is a top plan view of the lock casing with the cover removed, similar to Fig. 3 showing one of the latch bolts retracted,

Figure 5 is a plan view similar to Fig. 4 50 showing the two latch bolts retracted,

Figure 6 is a detail sectional view of a

portion of the lock casing and knob spindle,

Figure 7 is a detail sectional view taken on line VII—VII of Fig. 6 showing the rectangular portion of the knob spindle,

Figure 8 is a detail sectional view taken on line VIII—VIII of Fig. 6 showing the circular portion of the knob spindle and the operating arm for shifting one of the latch 65 bolts,

Figure 9 is a detail side elevational view, partially in section, of the lock casing,

Figure 10 is a perspective view of the lever plate of the lock mechanism,

Figure 11 is a perspective view of one of the catch levers, and

Figure 12 is a side elevational view of the key for operating the lock mechanism.

Briefly described, the present invention 75 refers to a door lock embodying a pair of tensioned bolts, each having a hook-shaped extension carried thereby. A knob spindle projecting through the lock casing is associated with a barrel or bearing having oppositely directed arms for engaging the extensions to shift the latch bolts against spring tension thereon. Key operated devices contained within the lock casing are adapted to be moved into engagement with 85 one of the latch bolt extensions for holding the latch bolt carrying said extension in an open position so that the other arm operated by the spindle may engage the other latch bolt extension for operating the latter in the 90 usual manner of a latch bolt.

Referring more in detail to the accompanying drawing the door lock is associated with a door 1 and a frame 2, the frame having a cutaway portion in the edge thereof to accommodate the socketed keeper 3 while the lock casing is countersunk within the door as shown in Fig. 3.

The lock casing embodies a bottom wall 4, side walls 5 and 6 and upper and lower walls 7 and 8 respectively, a cover plate 9 shown in Fig. 1 being associated with the lock casing and secured thereto in any suitable manner. Frame bars 10, 11 and 12 of angle formation extend between the upper and lower 100 walls 7 and 8 as clearly shown in Figs. 3, 4 and 5, the bar 10 constituting guides for the latch bolts 13 and 14 having latch heads 15, coil springs 16 surrounding the latch bolts 13 and 14 between the bar 10 and the latch 105 heads 15, normally to project the heads of the latch bolts outwardly of the lock casing

110

2
wall 5. The inner end of the bolt 13 carries a lateral angle extension 17 terminating in an inwardly directed hook 18, while the inner end of the latch bolt 14 carries a laterally directed angular extension 19 terminating in an inwardly directed hook 20 opposite to the extension hook 18, the side leg 21 connecting the extension 19 and hook 20 carrying an offset shoulder 22 while the rear face 10 of the extension 19 is provided with an inclined cam face 23.

The mechanism for shifting the latch bolts 13 and 14 embodies a knob spindle having a portion thereof rectangular in cross section as at 24 and a portion thereof cylindrical in cross section as at 25 with a knob 26 carried by each end thereof, the knob spindle extending through the walls of the lock casing intermediate the extension hooks 18 and 20. Operating arms for the latch bolts are carried by the knob spindle, the operating arm 26 being carried by a hub 27 secured to the rectangular portion of the knob spindle for engagement with the extension hook 18 while the arm 28 carried by the hub portion 29 has a pawl and ratchet connection 30 with the cylindrical portion of the knob spindle, the arm 28 being adapted for engagement with the extension hook 20.

In sliding the latch bolts 13 and 14 the arm 26 carried by the knob spindle is first moved into engagement with the extension hook 18 to shift the same to the dotted line 35 position illustrated in Fig. 3, at which time the arm 28 will be moved into engagement with the extension 19 of the latch bolt 14 to cause the same to move relative to the cylindrical portion 25 of the knob spindle and 40 dispose the same in an angular relation with respect to the arm 26. Upon releasing the pressure on the knob spindle the spring 16 upon the latch bolt 13 will again project the head 15 of said latch bolt and movement of the knob spindle in the opposite direction 45 will cause the arm 28 to engage the extension hook 20 to move the same to the position shown in Fig. 4.

To hold the latch bolt 14 retracted in the 50 position shown in Fig. 4, in the initial operation of the lock a dog 31 pivoted as at 32 to a pin carried by the bottom wall 4 of the casing and tensioned by the spring 33 is engaged by the cam 34 operated by the knob 55 35 to move the hook extension 36 of the dog 31 into engagement with the shoulder 32 of the extension arm 21, the cam being then disengaged from the dog and the frictional engagement between the dog and arm shoulder 22 being maintained against the tension 60 of the spring 33.

In order to hold the latch bolt 11 retracted and in an unlocked condition, key operated devices contained within the lock 65 casing are moved into engagement with the

extension arm 19 of the latch bolt 14 and the bar 10 of the lock casing, these devices including a lever plate 37 having an arm extension 38 provided with an opening 39 in the end thereof for pivotal mounting 70 upon the pin 40' carried by the frame bar 12. A plurality of catch levers 40 of the form shown in detail in Fig. 11 having openings 41 are pivotally supported upon the pin 42 projecting perpendicularly from 75 the lever plate 37. Each catch lever 40 carries a rearwardly directed shoulder 43 adjacent the free end thereof with a groove 44 in the outer face of the shoulder while a hook extension 45 projects from the opposite side of the catch lever adjacent the shoulder 43. The opposite end of the catch lever is provided with a terminal substantially V-shaped recess 45' forming an end hook 46. The catch levers 40 pivotally supported on the pin 42 of the lever plate 37 are separately tensioned by spring wires 47 having double coils 48 and 49, the coil 48 being associated with the U-shaped support 50 while the coil 49 is received on the 90 pin 51, the support 50 and the pin 51 being carried by the lever plate 37. The catch levers being under tension, the same have the hook extensions 45 thereof moved into engagement with the pin 52 carried by 95 the lever plate 37, the springs 47 engaging in the shoulder grooves 44. A key of the type shown in Fig. 12 having a stem 53 and a blade 54 having wards 55 is inserted through the key opening 56 in the opposite sides of the lock casing with the walls of the key hole of a like configuration to the blade of the key. By rotating the key in the proper direction, with the lever plate and catch levers in the position shown in 100 Figs. 3 and 4, the blade of the key is moved into engagement with the hook extensions 45 of the catch levers, the key shifting the catch levers to displace the engagement between the recessed ends 45' and the corner 105 of the frame bars 10 and 11 against the tension of the springs 47. Continued movement of the key causes the same to engage the lower edge 57 of the lever plate 37 to shift the lever plate upon the pivoted pin 110 40' causing the nose 58 of the lever plate to move into engagement with the inclined cam face 23 of the latch bolt extension 19 and further causing an engagement between the inner faces of the catch levers 40 and the side face of the frame bar 10. During this movement the lever plate causes a slight movement of the latch bolt 115 120 to relieve the frictional engagement between the dog 31 and the shoulder 22, permitting the spring 33 to disengage the dog from the shoulder, while the springs 47 125 maintain engagement between the lever plate and the latch bolt extension 19, and between catch levers 40 and the frame bar 130

130

10. In this position the latch bolt 14 is locked in a retracted position, permitting the latch bolt 13 to operate in the usual manner by the arm 26 engaging the extension hook 18. When it is desired to release the latch bolt 14 to permit the same to be projected in the casing for reception in the keeper 3 as shown in Fig. 3, the arm 28 is moved to engage the hook 20 of the latch bolt extension 19, a slight movement of the hook 20 relieving the frictional engagement between the nose 58 of the lever plate and the cam shoulder 23 of the latch bolt extension, at which time the springs 47 will function to lower the lever plate and disengage the catch levers from the frame bar 10, the catch levers returning to the position shown in Figs. 3 and 4 with the hooks 46 engaging the frame bar 10 and being further limited in their movement by the hooks 45 engaging the pin 52.

A sliding lock bolt 59 positioned in the casing and guided by the frame bar 12 has a cross pin 60 projecting from opposite sides of the casing and operable by a head 61, the lock bolt being employed in addition to the latch bolts 13 and 14 and being illustrated in the locked position in Fig. 3.

30 From the above detail description of the device, it is believed that the construction and operation thereof will at once be apparent, it being noted that the latch bolt 14 may be retained in the open position shown in Fig. 5 with the latch bolt 13 operating in the usual manner of a latch bolt for doors to control the opening and closing movement thereof, and while there is herein shown and described the preferred embodiment of the present invention it is nevertheless to be understood that minor changes may be made therein without departing from the spirit and scope of the invention.

45 What is claimed as new is:—

1. A lock of the type described comprising a casing, a pair of tensioned latch bolts slidably mounted therein, means for shifting the latch bolts, means for holding one of said latch bolts in a retracted position, said means including an extension carried by the last named latch bolt, a dog primarily engaging said extension, and a lever plate moved to engagement with said extension and disengaging the dog therefrom for returning the latch bolt to its operative position.

50 2. A lock of the type described comprising a casing, a pair of tensioned latch bolts slidably mounted therein, means for shifting the latch bolts, means for holding one of said latch bolts in a retracted position, said means including an extension carried by the last named latch bolt, a dog primarily engaging said extension, a lever plate moved

to engagement with said extension and disengaging the dog therefrom for returning the latch bolt to its operative position, a frame bar within the casing, and catch levers carried by the lever plate for engaging the frame bar. 70

3. A lock of the type described comprising a casing, a pair of tensioned latch bolts slidably mounted therein, means for shifting the latch bolts, means for holding one of said latch bolts in a retracted position, said means including an extension carried by the last named latch bolt, a dog primarily engaging said extension, a lever plate moved to engagement with said extension and disengaging the dog therefrom for returning the latch bolt to its operative position, a frame bar within the casing, and tensioned catch levers carried by the lever plate for engaging the frame bar. 75

4. A lock of the type described comprising a casing, a pair of tensioned latch bolts slidably mounted therein, means for shifting the latch bolts, means for holding one of said latch bolts in a retracted position, said means including an extension carried by the last named latch bolt, a dog primarily engaging said extension, a lever plate moved to engagement with said extension and disengaging the dog therefrom for returning the latch bolt to its operative position, a frame bar within the casing, catch levers carried by the lever plate for engaging the frame bar, and means for moving the lever plate into engagement with the extension. 95

5. A lock of the type described comprising a casing, a pair of tensioned latch bolts slidably mounted therein, means for shifting the latch bolts, means for holding one of said latch bolts in a retracted position, said means including an extension carried by the last named latch bolt, a dog primarily engaging said extension, a lever plate moved to engagement with said extension and disengaging the dog therefrom for returning the latch bolt to its operative position, a frame bar within the casing, tensioned catch levers carried by the lever plate for engaging the frame bar, and means for moving the lever plate into engagement with the extension. 105

6. A lock of the type described comprising a casing, a pair of tensioned latch bolts slidably mounted in the casing, lateral extensions carried by the latch bolts and each having an inwardly directed hook at the free ends thereof, a knob spindle journaled intermediate the hooks, and lateral arms carried by the knob spindle for alternately engaging said hooks to shift the latch bolts. 120

7. A lock of the type described comprising a casing, a pair of tensioned latch bolts slidably mounted in the casing, lateral extensions carried by the latch bolts and each having an inwardly directed hook at the free ends thereof, a knob spindle journaled inter- 125

130

mediate the hooks, lateral arms carried by the knob spindle for alternately engaging said hooks to shift the latch bolts, and means associated with one of said bolt extensions 5 for holding the same in a retracted unlocked position.

8. A lock of the type described comprising a casing, a pair of tensioned latch bolts slidably mounted in the casing, lateral extensions carried by the latch bolts and each having an inwardly directed hook at the free ends thereof, a knob spindle journaled intermediate the hooks, lateral arms carried by the knob spindle for alternately engaging said hooks to shift the latch bolts, means associated with one of said bolt extensions for holding the same in a retracted unlocked position, said means including a lever plate pivoted in the casing, tensioned catch levers 10 carried by said plate, and means engaging the catch levers and lever plate to move the same into engagement with said extension.

9. A lock of the type described comprising a casing, a pair of tensioned latch bolts 25 slidably mounted in the casing, lateral extensions carried by the latch bolts and each having an inwardly directed hook at the free ends thereof, a knob spindle journaled intermediate the hooks, lateral arms carried by the knob spindle for alternately engaging said 30 hooks to shift the latch bolts, means associated with one of said bolt extensions for

holding the same in a retracted unlocked position, said means including a lever plate pivoted in the casing, tensioned catch levers 35 carried by said plate, means engaging the catch levers and lever plate to move the same into engagement with said extension, and means for holding said extension in a position to be engaged by said lever plate and 40 thereafter freed from engagement with said extension.

10. A lock of the type described comprising a casing, a pair of tensioned latch bolts 45 slidably mounted in the casing, lateral extensions carried by the latch bolts and each having an inwardly directed hook at the free ends thereof, a knob spindle journaled intermediate the hooks, lateral arms carried by the knob spindle for alternately engaging said 50 hooks to shift the latch bolts, means associated with one of said bolt extensions for holding the same in a retracted unlocked position, said means including a lever plate pivoted in the casing, tensioned catch levers 55 carried by said plate, means engaging the catch levers and lever plate to move the same into engagement with said extension, means for holding said extension in a position to be engaged by said lever plate and thereafter 60 freed from engagement with said extension, and a sliding lock bolt within the casing.

In testimony whereof I affix my signature.
LUDWIK RZEPKA.
